United States Patent

Des. 236,033
Patented July 22, 1975

236,033

RESPIRATORY MASK

Gale E. Dryden, 5835 N. Tacoma Ave.,
Indianapolis, Ind. 46220

Filed Dec. 14, 1972, Ser. No. 315,206

Term of patent 14 years

Int. Cl. D29—02; D24—02
U.S. Cl. D83—1 K

Fig. 1

Fig. 2

Fig. 3

Fig. 4

Fig. 5

Fig. 6

FIG. 1 is a front view showing my new respiratory mask.
 FIG. 2 is a side view thereof.

FIG. 3 is a rear view thereof.

FIG. 4 is a section taken at line 4—4 in FIG. 2 and viewed in the direction of the arrows.

FIG. 5 is a top plan view thereof.

FIG. 6 is a bottom view thereof.

The left side view is a mirror image of the right side view shown in FIG. 2.

I claim:

The ornamental design for a respiratory mask, as shown and described.
